UNITED STATES PATENT OFFICE

HERBERT L. GLAZE, OF SOUTH PASADENA, AND FORREST G. STANFORD, OF LOS ANGELES, CALIFORNIA; SAID GLAZE ASSIGNOR TO GEORGE H. HYLAND, OF LOS ANGELES, CALIFORNIA

BEVERAGE-DISPLAY FOUNTAIN

Application filed December 3, 1927. Serial No. 237,415.

This invention relates to an apparatus for use in dispensing liquids and particularly pertains to a means and method for effecting display and agitation of the liquid to be dispensed.

An object of the invention is to provide a liquid dispensing and display apparatus in which the liquid will be displayed by being intermittently delivered to and discharged from a container, and in which the movement of the liquid will be automatically effected without directly subjecting it to the action of a pump.

Another object is to provide a means whereby the flow of liquid into the display container and its discharge therefrom will be effected by making and breaking a partial vacuum in the container.

Another object is to provide a means for making and breaking the partial vacuum which is simple in construction, durable and not liable to get out of order.

With the foregoing objects in view together with such other objects and advantages as may subsequently appear, the invention resides generally in the provision of a transparent display container associated with a dispensing tank or reservoir for containing the liquid to be displayed and dispensed, together with means whereby the liquid from the reservoir will be delivered to the container by suction induced in the latter and be discharged into the container until the latter is filled to a predetermined level and then by breaking the suction induced in the container to cause the liquid therein to gravitate back to the reservoir.

The invention further resides in the parts and in the combination, construction and arrangement of parts, hereinafter described and claimed and illustrated by way of example in the accompanying drawings, in which:

Fig. 1 is a diagrammatic view of the apparatus showing it partly in section and partly in elevation with portions broken away; the display container control valve being shown in its open position;

Fig. 2 is an enlarged detail in section as seen on the line 2—2 of Fig. 1;

Fig. 3 is a detail in section illustrating the display container control valve in its closed position;

Fig. 4 is a plan view of the operative mechanism with the display container removed;

Fig. 5 is an end view of the operating mechanism as seen in the direction of the arrow 5 in Fig. 4;

Figs. 6, 7, 8, 9 and 10 are diagrammatic views illustrating the manner in which the liquid is displayed in the display container;

Figs. 11 and 12 are sectional views taken on line 11—12 of Fig. 5 showing the operation of the main control valve.

Referring to the drawings more specifically, A indicates a tank or reservoir for containing a liquid to be dispensed, which liquid may be drawn from the reservoir by the usual dispensing means not necessary to be here shown, and B indicates a display container which is superimposed in relation to the reservoir A and is here shown as seated on the latter. This container may be of any suitable construction but preferably comprises a glass globe. Leading downwardly from the container and opening to the reservoir A is a tube 13 affording a communication between the interior of the reservoir and the interior of the container. Arranged within the tube 13 is a tubular stem 14 on the lower end of which is supported a valve 15 adapted to seat on the lower end of the tube 13; the valve 15 including a plate *a* loosely supported on a bead *b* on the lower end of the stem 14 and also including a gasket *c* seating on the plate *a* and adapted to seat on the lower end of the tube 13 when the valve 15 is in its closed position.

The stem 14 is open at its ends and affords a communication between the reservoir and the display container, when the valve 15 is in its closed position. The stem 14 is provided with guide flanges 16, which loosely cooperate with the inner face of the tube 13 in guiding the valve 15 to its seat, and mounted on the stem 14 and preferably arranged within the tube 13 is a float 17 which renders the valve and its stem partly buoyant. Leading from the upper portion of the container is a conduit 18 here shown as ex-

tending exteriorly thereof. The connection of the conduit 18 with the container 12 is preferably effected through a check valve 19 here shown as embodying a valve housing *d* interposed between the end of the conduit 18 and the interior of the container in which housing is mounted a dependant valve stem *e* carrying a valve *f* on its upper end; the stem *e* being supported in a guide *g* and the valve *f* being adapted to be moved upwardly against the valve seat *h* to close the communication between the container and conduit. In event liquid in the container should inadvertently rise beyond a predetermined level, the check valve is closed by the action of a float *i* carried on the lower end of the stem *e*.

The conduit 18 serves as a means through which air may be exhausted from and delivered to the display container; it leading from the container to a suitable operating mechanism, a preferred form of which is here shown as embodying a suction pump 20 the intake side of which communicates with the interior of the display container through the conduit 18, a main control valve 21 interposed in the communication between the pump and container, a timing mechanism 22 for actuating the valve 21, and a source of power here shown as comprising an electric motor 23 for actuating the pump, the timing mechanism and the main control valve.

The valve 21 is here shown as embodying a pair of plates 24 and 25 between which is interposed a turnable disk 26; the plates 24 and 25 and disk 26 being assembled on a bolt 27 projecting from a standard 28. The bolt serves as a pivot on which the disk 26 may turn. A spring 29 bears between an abutment 30 on the bolt and the outer plate 24 and by its pressure maintains the plates 24 and 25 under yieldable pressure against the opposite faces of the disk. The plates 24 and 25 are formed with two pair of opposed openings; the openings *j* and *k* on the plate 25 communicating with a conduit 31 communicating with the conduit 18 through a trap 32. The openings *l* and *m* in plate 24 are designed to be alternately placed in communication with the openings *j* and *k* through the medium of the valve disk 26, which latter is formed with a pair of openings *n* and *o* for this purpose. The opening *l* leads to atmosphere and affords an air intake for the display container when the valve disk 26 is positioned with the opening *o* registering with the openings *l* and *j* as shown in Fig. 11. The opening *m* communicates with a conduit 33 leading to the intake side of the pump 20 and affords an exhaust for the display container when the valve disk 26 is positioned to dispose the opening *o* and register with the openings *k* and *m* as shown in Fig. 12.

In order to afford a supply of air to the pump, when its communication with the dis-

play container is cut off, the valve disk 26 is formed with a channel *p* as shown in Fig. 11; this channel being formed on the face of the disk 26 adjacent the plate 24, which channel is so located that when the valve disk 26 is disposed with the port *n* registering with the intake port *l* and communication between the ports *k* and *m* is closed, the channel *p* will register with the port *m* and by reason of the channel opening to the periphery of the disk 26 then affords a communication between the conduit 33 and atmosphere.

A suitable mechanism may be provided for effecting actuation of the main control valve to alternately effect exhaust of air from the container and to deliver air thereto. The means here shown embodies a revoluble wheel 34 carrying a pair of opposed cams 35 and 36 adapted on rotation of the wheel to successfully engage a pin 37 carried by the valve disk 36 in such fashion as to rock the valve disk from side to side; the wheel 34 being mounted on a shaft 38 extending at right angles to the disk 36. The wheel 34 with the cams 35 and 36 constitute a portion of the timing mechanism and as a means of varying the intervals of the actuation of the disk valve to vary the moments of exhaust and intake of the display container, the cams 35 and 36 are adjustably mounted on the wheel 34 and for which purpose are here shown as embodying plates, which are detachably secured to the wheel 34 by means of screws 39; the wheel 34 being formed with a series of threaded openings 40 for reception of the screws 39 so arranged as to permit the cams being spaced various distances apart and at various points peripherally of the wheel.

As a means for driving the wheel 34, the shaft 38 is here shown as fitted with a gear wheel 41 meshing with a driving worm 42 carried on a shaft 43 adapted to be driven through a train of gears, indicated generally at 44, from the motor 23.

In the operation of the invention, starting of the motor 23 will set the pump 20 in operation and will effect rotation of the wheel 34 which latter will oscillate the valve disk 26 as before described. When the valve disk 26 is disposed to place the ports of the main control valves *j*, *l* and *n* in communication, the interior of the display container will then be open to atmosphere so that a liquid within the container, by reason of being higher than the level of the liquid in the reservoir, will gravitate through the tube 13 into the reservoir as indicated in Fig. 1; the valve 15 being opened under weight of the column of the liquid imposed thereon to permit discharge of the liquid from the container. While this discharge of liquid from the container is taking place, the valve disk 26 is maintained stationary. On the cam 36

engaging the pin 37 and rocking the valve to close the air intake and effect communication between the interior of the display container and the suction pump through the communicating ports *k*, *o* and *m* through the main control valve as shown in Fig. 12, a suction will be induced in the container creating a partial vacuum therein, which in reducing the atmospheric pressure in the container will cause the valve 15 to close under the combined action of difference in atmospheric pressure in the reservoir and the buoyant effect of the float 17. On closing of the valve 15, the suction induced in the container will cause liquid from the reservoir to flow upwardly through the stem 14 and be delivered in the container preferably in the form of a fountain as illustrated in Fig. 7. The liquid will thus continue to flow into the container for an interval of time, gradually filling the container to a predetermined level. During this filling operation, the incoming fountain of liquid will maintain the volume of liquid in the container in a state of agitation. This intake of the liquid endures until the main control valve is again actuated by the cam 35 to cut off the communication between the pump and the container and to break the vacuum in the latter by admitting air to the container through the ports *j*, *l* and *n* as before described. As soon as the suction in the container terminates, the intake of liquid will stop whereupon the liquid in the container will cease to be turbulent and because of the valve 15 when being opened under the weight of the liquid causing it to flow back into the reservoir, the level of the liquid in the container will gradually fall.

In this manner, the liquid is alternately delivered to and discharged from the container; the container being empty or substantially empty for an interval of time then being filled to a predetermined level through an interval of time by a fountain which is gradually submerged and the liquid then maintained in a state of agitation for another interval, and finally rendered quiescent and its level slowly lowered until the container is again substantially emptied. This display action is illustrated diagrammatically in Figs. 6 to 10, inclusive; Fig. 6 showing the container as practically empty; Fig. 7 showing the initial inflow of the liquid into the container in the form of a fountain; Fig. 8 showing the manner in which the fountain is gradually submerged; Fig. 9 showing the fountain as submerged and the liquid in a state of turbulence; and Fig. 10 showing the liquid in a placid state, while flowing from the container.

It will be observed that during operation the level of the liquid in the container constantly varies and is not maintained for any appreciable length of time at a predeter-

mined level, and that while entering the container the liquid is agitated and turbulent and while being discharged from the container it is relatively placid.

The trap 32 is provided as a means for collecting condensates due to moisture carried off with the air content of the container so as to prevent such moisture from fouling the main control valve and pump. The check valve 19 while not essential to the operation of the device may be employed as a precaution against excessive filling of the display container.

The invention is particularly applicable for use in the display of beverages in beverage dispensers such as are used in dispensing fruit juices and the like, but it may obviously be employed for the display of various liquids.

While we have shown and described a specific embodiment of our invention, we do not limit ourselves to the exact details as shown but may employ such changes, modifications and equivalents, as come within the meaning and scope of the appended claims.

We claim:

1. In a liquid display apparatus, a reservoir, a display container in communication with said reservoir, means for delivering liquid from said reservoir to said container by suction induced in the latter, and automatic means for controlling the intake of liquid to the container operable to effect discharge of liquid therefrom.

2. In a liquid display apparatus, a reservoir, a display container in communication with said reservoir, means for creating a partial vacuum for said container whereby liquid will be inducted from the reservoir into the container, and automatic means for intermittently breaking the partial vacuum in the container, whereby ejection of liquid therefrom will be effected in alternation with the induction thereof.

3. In a liquid display apparatus, a reservoir, a display container in communication with the reservoir, a suction pump for creating a partial vacuum in said display container, whereby liquid from the reservoir will be inducted into the container, and a main control valve automatically operable to alternately make and break communication between the suction pump and the container and adapted to admit air to the container whereby the liquid in the container will be caused to flow therefrom.

4. In a liquid display apparatus, a reservoir, a display container in communication with the reservoir, a suction pump for creating a partial vacuum in said display container, whereby liquid from the reservoir will be inducted into the container, a main control valve operable to alternately make and break communication between the suction pump and the container and adapted to admit air

to the container whereby the liquid in the container will be caused to flow therefrom, and means for automatically timing the operation of said valve whereby induction and eduction of the liquid to and from the container will be alternated at predetermined intervals.

5. In a liquid display apparatus, a reservoir, a container communicating with the reservoir, means for inducing a partial vacuum in said container, whereby liquid will be drawn into the container from the reservoir, and means operable at predetermined intervals for intermittently breaking the partial vacuum in the container and cooperating with said last named means in effecting alternate delivery of liquid to and its discharge from the container.

6. In a display apparatus, a reservoir, a display container, a tube affording communication between the container and reservoir the lower end of which extends into liquid in the reservoir, a tubular stem in said tube, a valve on said stem for closing said tube through which said stem opens, said valve being adapted to be opened under weight of liquid in the container, means for inducing a partial vacuum in said container operable to effect closing of said valve and whereby liquid from the reservoir will be delivered to the container through the tubular stem, and means for intermittently breaking the vacuum in the container.

7. In a display apparatus, a reservoir, a display container, a tube affording communication between the container and reservoir the lower end of which extends into liquid in the reservoir, a tubular stem in said tube, a valve on said stem for closing said tube through which said stem opens, said valve being adapted to be opened under weight of liquid in the container, means for inducing a partial vacuum in said container operable to effect closing of said valve and whereby liquid from the reservoir will be delivered to the container through the tubular stem, means for imparting buoyancy to said stem and valve, and means for intermittently breaking the vacuum in the container.

8. In a liquid display apparatus, a reservoir, a container arranged above the reservoir and communicating therewith, a suction pump, a communication between the intake side of said suction pump and said container, an oscillatory valve interposed in said communication operable alternately to open and close the communication between the pump and container and to alternately open and close the container to atmosphere, and means for periodically actuating said valve.

9. In a liquid display apparatus, a reservoir, a container arranged above the reservoir and communicating therewith, a suction pump, a communication between the in-

take side of said suction pump and said container, an oscillatory valve interposed in said communication operable alternately to open and close the communication between the pump and container and to alternately open and close the container to atmosphere, a revolute wheel, a pair of cams on said wheel and means whereby rotation of said wheel will cause said cams to effect actuation of said valve.

10. In a liquid display apparatus, a reservoir, a container arranged above the reservoir and communicating therewith, a suction pump, a communication between the intake side of said suction pump and said container, an oscillatory valve interposed in said communication operable alternately to open and close the communication between the pump and container and to alternately open and close the container to atmosphere, a revolute wheel, a pair of cams on said wheel, means whereby rotation of said wheel will cause said cams to effect actuation of said valve, said cams being relatively adjustable on said wheel, whereby timing of the operation of said valve may be varied.

11. In a liquid display apparatus, a reservoir, a display container communicating with said reservoir, a pipe leading from the upper portion of said container, means for inducing a suction in said container through said pipe whereby liquid from the reservoir will be drawn into the container, a normally open check valve operable by liquid in the container for closing communication between the container and said pipe, and means associated with said suction means for intermittently breaking the suction induced in said pipe, at predetermined intervals.

12. In a liquid display apparatus, a reservoir, a display container communicating with the reservoir, a pipe leading from the upper portion of the container, means for exhausting air from said container through said pipe, a trap in said pipe for condensing moisture, and means associated with said suction means for intermittently opening said pipe to atmosphere, at predetermined intervals.

13. The method of displaying a liquid consisting in delivering the liquid to a display container by suction induced in the latter and automatically breaking the suction at predetermined intervals to cause the liquid to gravitate from the container, thus forming a closed cycle of operations.

14. The method of displaying a liquid consisting in gradually delivering the liquid to a display container in the form of a fountain created by suction induced in the container, whereby inflowing accumulating liquid in the container will be rendered turbulent, and automatically breaking the suction at predetermined intervals by admit-

ting air to the container, whereby the liquid in the container is rendered relatively placid and is caused to be discharged from the container by gravity, thus forming a closed cycle of automatic operations.

5 In testimony whereof, we have affixed our signatures.
